UNITED STATES PATENT OFFICE.

HENRY L. DOLE, OF HAVERHILL, MASSACHUSETTS.

DESIGN FOR A HANDLE FOR SPOONS, &c.

SPECIFICATION forming part of Design No. 20,543, dated March 3, 1891.

Application filed January 19, 1891. Serial No. 378,861. Term of patent 7 years.

To all whom it may concern:

Be it known that I, HENRY L. DOLE, a citizen of the United States, residing at Haverhill, in the county of Essex and State of Massachusetts, have invented and produced a new and original Design for Handles for Table-Ware, of which the following is a specification, reference being had to the accompanying drawing, forming part thereof.

10 The drawing shows a front or face view of my newly-designed handle, it being in this embodiment of my invention represented as applied to a spoon; but the handle may be applied equally well to a fork or other table-ware.

15 Odd spoons, forks, &c., are now in very considerable demand, and many manufacturers have selected odd and quaint designs to commemorate historical and other subjects.

20 My newly-designed handle is intended as a

souvenir in memory of the aged poet Whittier; and I have in embodying my design shown a representation of the house *a* in which the poet Whittier was born, and have set the house in a field with parts of a tree at 25 either side, as at *b c*, a roadway being represented at *d*.

The leading feature of my design is therefore the representation of the Whittier homestead in a field.

30

I claim—

The design for handle for table-ware, as shown and described.

In testimony whereof I have signed my name to this specification in the presence of 35 two subscribing witnesses.

HENRY L. DOLE.
